UNITED STATES PATENT OFFICE.

ROBERT WILSON MORE, OF CHICAGO, ILLINOIS.

SYSTEM OF OPERATION OF AUTOMATIC TYPEWRITERS AND DEVICES THEREOF.

Application filed April 2, 1921. Serial No. 458,101.

To all whom it may concern:

Be it known that I, ROBERT WILSON MORE, a citizen of the United States, residing at Chicago, in the county of Cook and State of Illinois, have invented a new and useful Improvement in Systems of Operation of Automatic Typewriters and Devices Thereof, of which the following is a specification.

My invention relates to an improvement in systems of operation of automatic typewriters and devices thereof in which I provide for the simultaneous and automatic operation of a plurality of typewriting machines from the same controlling or actuating devices together with means for connecting or disconnecting any one of the typewriting machines as desired, and I further provide in connection with the controlling or actuating devices, two controlling mechanisms, each for actuating a separate group of said typewriting machines, the controlling mechanism in the one case being preferably automatic in its operation, as for example devices actuated by a record strip as commonly used in connection with automatic piano players, while the other actuating mechanism may be operated manually so that the typewriting machines connected therewith may be operated to write any special subject matter desired. By my invention I also provide devices for interchanging the relation between the controlling mechanisms and the groups of typewriting machines so that either group as desired may be operated by the automatic controlling and actuating mechanism or by the manual operating mechanism. By my invention I further provide devices for connecting each typewriting machine or disconnecting the same so that whether the actuating mechanism be automatic or manual, any one or more of the machines of either group may be actuated as desired. For certain parts of the work it is desirable to operate one machine at a time by means of manual control, as for example in filling in individual headings in letters where the body of the letter is to be the same for a large number of letters to be written, and in doing this with my system, the attendant, after placing the paper in the machine, inserts the heading by operating the machine through the manual controlling mechanism. This first machine with its letter sheet in readiness for the body portion of the letter is then disconnected from the controlling mech-

anism, a second machine of the same group is connected and similarly prepared and so on one after another for the same group, so that when the last machine has been prepared the entire group is in readiness for the automatic operation. During this interval of preparation of the machines of the group referred to all of the machines of the other group are preferably being operated simultaneously by the automatic controlling mechanism to write on the several letter sheets in the different machines of the second group, the subject matter previously punched or placed on the record strip actuating the automatic controlling mechanism. The record sheet or strip is preferably endless so that it passes through the automatic controlling mechanism repeatedly and the most effective results are secured by having such a number of machines in each group that the time required for the attendant to remove the written letters from each machine of one group, insert a fresh sheet in each machine and place the proper heading on the sheet so that each machine of the group will be in readiness for the body portion of the letter, is substantially equal to the time required for the automatic controlling mechanism to simultaneously write the body portion of the letter on all of the machines of the other group. In this way the record strip is kept in operation practically continuously and no time is lost. Any number of machines may be used in each group depending upon the circumstances and the total number of letters to be written, and if desired the headings may be put in by manual operation of the machines directly instead of through the manual controlling mechanism, in which case several attendants may, if necessary be engaged in preparing the machines of one group while the machines of the other group are being automatically operated. If desired both groups of machines may be connected for operation by either controlling mechanism.

In carrying out my invention I find that electromagnets may be used effectively in connection with suitable switching and controlling devices connected with the circuits of the magnets for securing the operation above referred to and in connection with such an electric system of operation I provide two groups of relays, each connected with the corresponding group of machines, contact fingers controlled by the record strip

for closing individual circuits corresponding in number with the number of relays in each group and individual switch contacts adapted to be closed by the operation of a standard typewriting machine key-board as a part of the manual controlling mechanism, together with switching devices for connecting either the contact fingers of the automatic controlling mechanism or the individual switch contacts of the manual controlling mechanism with either group of relays as desired, the currents flowing through these circuits being relatively preferably small to prevent undue arcing and wear at the contacts controlled by the contact fingers and at the individual switch contacts of the manual controlling mechanism. In addition switching mechanism is provided in the circuits extending from the contacts of each group of relays so that electric circuits connecting with the actuating magnets of the several typewriting machines of each group may be connected to or disconnected from the relay contacts of the corresponding group as desired, these connections being in parallel relation and the relay contacts being constructed to take care of the relatively large currents required to operate the typewriter electromagnets of either group when connected in parallel relation.

My invention further provides improved devices of the kind set forth for operating a typewriting machine electrically and also improved devices for effecting the various controls referred to.

My invention will best be understood by reference to the accompanying drawings showing a preferred embodiment thereof in which—

Fig. 1 shows in front elevation one of the typewriting machines employed in my system.

Fig. 2 is a detail bottom view of the electric switch actuated at the end of the carriage return.

Fig. 3 is a side elevation of the typewriting machine shown in Fig. 1,

Fig. 4 is a detail end view of the electric switch controlling the carriage return clutch,

Fig. 5 is a plan view of the carriage of the machine shown in Figs. 1 and 3,

Fig. 6 shows in side elevation somewhat diagrammatically the devices and electromagnets for actuating the tabulating mechanism of the machine shown in Figs. 1 and 3,

Fig. 7 shows in rear elevation a part of the mechanism employed to operate the said tabulating mechanism,

Fig. 8 shows in a view similar to Fig. 7 certain of the parts of Fig. 7 in their alternate position,

Fig. 9 shows in longitudinal sectional view one of the electromagnets employed to operate the machine shown in Figs. 1 and 3,

Fig. 10 shows in plan view a spring disk employed in the magnet construction shown in Fig. 9,

Fig. 11 is an edge view of the disk shown in Fig. 10,

Fig. 12 shows in plan view the automatic controlling mechanism for making contact through the contact fingers of the individual circuits for actuating one group of relays of the controlling mechanism and also shows one of said groups of relays,

Fig. 13 is a sectional view of the parts shown in Fig. 12 taken along the line 13—13,

Fig. 14 is an end view of the motor control switch shown in Fig. 13,

Fig. 15 is a rear elevation of the left hand side wall and adjacent relay mechanism shown in Fig. 12,

Fig. 16 is a plan view of a part of the contact roller and record strip, showing the relation of the contact openings to the contact roller,

Fig. 17 is a plan view of the complete controlling mechanism of my system with the exception of the manual controlling mechanism, this view showing the parts somewhat diagrammatically and with the cover of the cabinet of the controlling mechanism and the manual controlling mechanism removed,

Fig. 18 is a front elevation of the controlling mechanism cabinet shown in Fig. 17,

Fig. 19 is a diagrammatic view taken on a vertical plane through the manual controlling mechanism,

Fig. 20 is a detail view of one of the contact strips employed in connection with the switch contacts shown in Fig. 19,

Fig. 21 is a plan view of the switching and connecting devices shown in Fig. 17 for connecting or disconnecting one of the typewriting machines,

Fig. 22 is a sectional view of the parts shown in Fig. 21 taken along the line 22—22,

Fig. 23 is a vertical sectional view to an enlarged scale through one of the yokes for effecting simultaneous operation of all of the connecting switches for one group of machines,

Fig. 24 is a sectional view to an enlarged scale of the reversing switch shown in Fig. 17 taken along the line 24—24,

Fig. 25 is a plan view of the contact roller or commutator shown in Fig. 24, and

Fig. 26 is a diagrammatic view of the circuit connections employed in my system.

Similar numerals refer to similar parts throughout the several views.

As shown in Figs. 1 and 3 the typewriting machine employed in my system, which may as to its mechanical construction be of standard type, consist of a frame 10, the key bars 11 of which have connected with them operating wires 12 extending downwardly to the plungers 13 of electromagnets 14, which electromagnets are preferably of

the solenoid type to secure most effective operation. The magnets are preferably arranged from front to rear in arcs of circles to permit making the connections by the 5 wires 12 to the key bars 11 in most effective manner, there being one of the electromagnets for each of the parts operated manually in actuating a standard typewriting machine. The magnets are supported by a suitable 10 frame 15 extending downwardly from the base of the typewriting machine and this frame also supports other operating mechanism to be described. For convenience the space bar 16 is connected in a similar 15 manner to that described with a similar electromagnet 17 supported above the magnets 14 on the frame work 15 and another electromagnet 18 of similar type is similarly connected with devices for in part actuating 20 the tabulating key mechanism in a manner to be described.

Each of the electromagnets is preferably constructed as shown in Fig. 9 and has a single actuating coil 14^a surrounded by a 25 tubular shell 14^b, the coil 14^a being wound on a non-magnetic sleeve 14^c. A core 14^d extends from a magnetic base plate 14^e to substantially the mid-portion of the sleeve 14^c and a plunger 13 is provided to be moved 30 into the sleeve 14^c towards the core 14^d by the magnetic action when current flows in the coil. A magnetic bar 14^f closes the upper end of the magnet with a central opening of substantially the size of the bore of the 35 sleeve 14^c. The upper end of the plunger 13 is engaged by an adjusting screw 14^g which passes through a yoke 14^h, the upper end of the yoke being connected with a block 14^m of insulating material, which block is 40 connected with one of the wires 12. The screw 14^g is provided with lock nuts on either side of the yoke 14^h so that any desired adjustment of the plunger 13 may be secured and maintained. A disk 14ⁿ of non-magnetic 45 material is provided on the upper end of the core 14^d, this disk being made as indicated in Figs. 10 and 11 with a number of radial cuts extending nearly to its center and with the edges of the cuts or slots bent 50 slightly in opposite directions so that the disk, which preferably is of spring material, such as spring brass or bronze, will cushion the impact of the plunger when it is forcibly drawn into the sleeve 14^c against the disk. The disk serves several useful 55 functions, for it not only cushions the impact referred to, but in addition it serves as an anti-sticking medium and by its spring action, it imparts an upward impulse to the plunger 13 immediately upon the de-energization of the electromagnet and thus contributes in large measure to the quick return 60 of the key bar connected therewith.

The typewriting machine is provided with 65 adjustable margin stops 19, 19^a engaging a

rod 20 so that movement of the typewriter carriage 21 to the position for beginning a new line, engages the stop 19 wherever it may be placed and imparts a small amount of longitudinal movement to the rod 20 70 against the action of the spring 22, which movement causes engagement between the right hand end of the rod 20 and the upper end of a lever 23 pivotally supported at 24 by a bracket extending from the frame 10. 75 The lever 23 carries at its lower end, a block 25 of conducting material insulated from the lever 23, which, upon the movement of the lever referred to, is moved between switch contacts 26 and 27, the relation of these parts 80 being more clearly shown in Fig. 2. The contacts 26 and 27 are supported by a suitable block of insulating material from the frame 10 of the machine. Immediately upon the release of the carriage return 85 mechanism in a manner to be described, the lever 23 is moved by a spring 28 to disengage the contact block 25 from the switch contacts 26 and 27.

The return of the carriage 21 to its position for writing a new line is accomplished 90 as follows: A motor 29 is supported by the frame work 15 to drive by a belt 30 a pulley 31 secured to one end of a shaft 32 supported in suitable bearings on the frame work so 95 that its other end carries a magnetic clutch 33. The clutch 33 is provided with a winding 34 the ends of which are connected with contact rings 35 and 36 carried by and insulated from the shell of the clutch and on 100 these contact rings brushes 37 and 38 are supported by a bracket carried by the frame work 15. The shaft 32 terminates at about 105 the mid-portion of the clutch coil and serves as its core. A second shaft 39 is supported 110 in suitable bearings carried by the frame work 15 in line with the shaft 32 and its right hand end as shown in Fig. 3, enters the coil 34 to form the plunger of the magnetic clutch. A disk 40 of magnetic material is 115 rigidly carried by the shaft 39 so that when current passes through the coil 34 the shaft 39 and the disk 40 are moved to the right against the action of a spring 41 to bring the disk into engagement with the end of the shell of the clutch and the ends of the shafts 39 and 32 together. For this condition of 120 the parts, the shaft 39 is driven and a drum 42 carried by the shaft 39 is rotated to wind up a cord or band 43 which extends upwardly from the drum, over the guide roller 44 rigidly supported from the frame 10 of the machine and then horizontally to engage a 125 rod 45 connected with the return and line spacing lever 46 of the carriage. The relation of the latter parts is more clearly shown in Fig. 5. The carriage return is continued as described until the contacts 26 and 27 are connected by the contact block 25 which energizes the electromagnet 47, the operation 130

of which magnet breaks the circuit through the coil 34 and releases the disk 40 under the action of the spring 41 thus stopping the driving of the shaft 39. The circuit of the coil 34 is closed through contacts 48 and 49 by a contact block 50 carried by and insulated from a lever 51 pivotally supported at 52 on the frame work 15. The magnet 47 is connected with the lever 51 by a rod or wire 53 so that when the magnet 47 is energized, the contact block 50 is moved from engagement with the contacts 48 and 49 and a second magnet 54 is connected to the other end of the lever 51 so that when it is energized the contact block 50 is moved into engagement with the contacts 48 and 49, the relation of the latter parts being more clearly indicated in Fig. 4. The contacts 48 and 49 are carried by a block of suitable insulating material secured to the frame work 15. A third electromagnet 47^a similar to the electromagnet 47 and similarly connected to the lever 51 is also provided for a purpose to be described. As a result of the construction described when the magnet 54 is energized which is done at the end of a written line in a manner to be described, the circuit of the coil 34 is closed, the disk 40 is attracted, the shaft 39 is rotated and the carriage is returned as described and at the end of its return movement the closing of the contacts 26 and 27 energizes the magnet 47 which disconnects the contacts 48 and 49 from each other and thus interrupts the circuit through the coil 34 and releases the carriage return mechanism. The motor 29 is intended to be operated continuously during the operation of the machine.

To provide for proper operation of the tabulating key by the momentary current impulse delivered by the controlling mechanism, the devices shown in Figs. 6, 7 and 8 are employed. As shown in these figures the tabulating key 11^a is connected with an actuating magnet 14^r so that energization of the magnet operates the key, rotates the lever 55 pivotally supported at 56 and connected with the key 11^a, and moves the rod 57, thus rocking the bar 58 on its end bearings 59 to release the spacing mechanism of the machine in the usual manner and permitting the carriage to move until the tabulating stop is brought into operation. The current impulse energizing the magnet 14^r is momentary and to provide against the release of the key lever 11^a bringing the spacing mechanism of the carriage into operation before the tabulating stop has reached its proper position, the following devices are employed: The bar 58 is provided with a rearwardly projecting arm 60 which as more clearly shown in Fig. 7, rests on a shoulder on the upper end of a bell crank lever 61 pivotally supported at 62 from the frame 10 of the machine. The lever 61 is engaged by

a spring 63 so that when the bar 58 is rocked by energization of the magnet 14^r in the manner above described, the arm 60 is raised to a position above a screw 64 carried by the upper end of the lever 61 and the action of the spring 63 moves the screw under the arm 60 as indicated in Fig. 8, thus holding the bar 58 in its rotated position and insuring that the carriage shall complete its movement until further movement is prevented by the tabulating stop, regardless of whether the actuation of the key bar 11^a is momentary or not. The record strip employed in the controlling mechanism is provided with two perforations for engaging different contact fingers, the first one of said fingers being first permitted to make contact with the contact roller to energize the magnet 14^r and sufficiently thereafter to certainly permit movement of the carriage until stopped by the tabulating stop, a second perforation is provided in the record strip for the second contact finger to energize the magnet 18 which is connected by the rod 65 with the lower end of the lever 61, which action moves the lever against the action of the spring 63 and permits the arm 60 to again engage the shoulder at the upper end of the lever 61 and thus returns the tabulating mechanism to its normal position. The screw 64 is held in desired adjustment by means of a lock nut as indicated.

The typewriting machine shown in the figures referred to is preferably of the shift key type to reduce the number of circuits and magnets required, although I do not limit myself to the actuating of any particular type of typewriting machine, and with a machine of the shift key type, it is preferable that the shifting operation shall be effected by first actuating the shift key through its proper magnet, that will lock the parts in their shifted position so that a momentary electric impulse will effect and retain the shifted condition, after which another magnet is energized, at the end of the writing of the upper case characters, to actuate the shift key release of the mechanism of the machine.

The controlling mechanism employed to control the circuits of the several typewriter magnets is shown in Figs. 12-16 inclusive. This mechanism consists of a frame work 66 in which a feed roller 67 is mounted to rotate in suitable bearings on the shaft 68. The shaft 68 has loosely mounted thereon a worm wheel 69 engaged by a worm 70 carried by a shaft 71 to which a pulley 72 is rigidly secured. The shaft 68 also carries a grooved clutch member 68^a splined thereon for engagement with a clutch member 69^a carried by the worm wheel 69, an operating lever 68^c pivotally mounted on a fixed support at 68^d being provided to engage the member 68^a to move it into or from engage-

ment with the member 69^a as desired. A crank 68^b is secured to the end of the shaft 68 to rotate the same when the clutch members are disengaged, to facilitate adjusting 5 the record strip as desired. The pulley 72 is engaged by a belt 73 driven by a small pulley 74 carried by the shaft of a motor 75, which motor is supported by the frame work 66. The motor circuit is controlled 10 by a contact block 76 and switch contacts 77 and 78, said contacts being mounted on a block of insulating material carried by the frame work 66. The contact block 76 is carried by and insulated from a lever 79 15 pivotally mounted at 80 on the frame work 66, said lever having connected thereto on opposite sides of its pivot, the plungers of electromagnets 81 and 82 as a result of which energization of the magnet 82 moves 20 the block into engagement with the contacts 77 and 78 and energization of the magnet 81 moves the block 76 from engagement with said contacts. The roller 67 as more clearly shown in Fig. 13 has strips of insulating material 67^a inserted in its surface longitudinally, leaving narrow strips of conducting material between them which strips of conducting material are a part of, or are carried by the body portion of the 25 roller 67 which is also of conducting material. The roller 67 is provided at each end with driving pins 67^b for engaging regularly spaced apertures 83^a formed in each edge of the record strip 83 as indicated in 30 Fig. 16, so that each of the circuit controlling apertures 83^b through the record strip 83 will be brought into registry with one of the conducting strips of the roller 67, the apertures 83^b being of greater extent longitudinally of the record strip than the width 35 of the conducting strips of the roller 67 for a purpose to be explained. Pressure rollers 84 and 85 are mounted adjacent the roller 67 to insure that the record strip 83 shall be 40 held in proper relation to the circuit closing devices. A series of contact arms 86 is secured to a strip of insulating material 87 hinged at 88 to the frame work of the controlling mechanism and each of these 45 arms carries at its outer end a plurality of brush wires 86^a bent at their outer ends to engage the surface of the record strip 83, which record strip is of thin pliable insulating material, such for example as paper or 50 similar fibrous material. There are as many of the arms 86 as circuits to be controlled by the mechanism and apertures 83^b are formed in the record strip 83 in line with each arm where it is desired to close 55 the circuit controlled by said arm and its brush wires. When one of the said apertures 83^b passes under the corresponding brush wires, the ends of the wires drop into the aperture under their spring action and 60 first rest upon one of the insulating strips 65 67^a and immediately thereafter the adjacent conducting strip of the roller 67 engages said brush wires to make electric contact between the corresponding arm 86 and the body portion of the roller 67 and therefore with the frame work 66 with which the body portion of the roller is in electrical connection. Immediately thereafter the 70 said conducting strip passes from under the said brush wires which thereupon rest on the next succeeding insulating strip 67^a thus breaking the circuit before the brush wires are lifted by the edge of the aperture 83^b. In this manner any arcing that takes place 75 at the ends of the brush wires, occurs at a distance from the edges of the apertures 83^b, which prevents charring the edges of the apertures and damaging the record strip. The pressure roller 85 is carried by 80 spring arms 89 secured to the bar 87 and a bent wire 90 is pivotally connected at its ends as indicated at 91 so that said bent wire will hold the roller 85 in the raised position indicated in Fig. 13 when it is desired 85 to insert or remove the record strip. Raising the roller 85 moves the bar 87 and the contact arms carried thereby to the position indicated in Fig. 13 against the action of one or more springs 92 which normally hold the bar in a position bringing the 90 brush wires into engagement with the record strip. The roller 67 is provided at the left hand end as shown in Fig. 12, with a spring operated bearing stud 93 having an end knob 94 by which the stud may be removed from engagement with the roller, the other end of the roller preferably having a slot or slots 95 for engaging a pin or pins 96 carried by the shaft 68 so that with the stud 93 withdrawn from the roller, the 95 roller may readily be removed from the machine to facilitate removing or inserting the record strip. The roller 84 is similarly provided with a spring actuated bearing stud 97 to permit its removal from the machine when desired. 100

Besides the circuit controlling mechanism described, the frame 66 carries relays 98, there being one relay for each of the contact arms 86 for the arrangement shown 105 in Fig. 12. These relays together constitute a first relay group and in practice I find it desirable to employ a second similar relay group to secure most effective operation of the system in a manner to be described. As indicated in Fig. 12 the relays are arranged 110 in rows across the frame work and as they are all of the same construction it will be necessary to describe but one of them as for example the relay 98^a shown in Fig. 13. 115 The plunger of the relay 98^a is connected by a rod 98^b with a spring arm 99 mounted on a bar 100 of insulating material which extends throughout the corresponding row of 120 relay mechanisms to support all of the 125 130

6

spring arms of the relays of said row. The arm 99 carries at its free end a contact 101 adapted when operated to engage a contact 102 mounted on a common conducting bar 103 extending throughout the row of corresponding relays, which conducting bar in turn is mounted on a bar 104 of insulating material which also extends throughout said row of relays. A rigid rod 105 is supported by the frame work over the free ends of the arms 99, said rod 105 being covered with suitable insulating material such as rubber tubing 106 to prevent electrical contact between the rod and the arms, said rod serving as a back stop for said arms. The relays 98 are of the same general construction as the magnets 14, the principal difference being their energizing windings. Each of the relay windings consists of a large number of turns of fine wire to reduce the current through the winding and therefore through the corresponding brush wires 86^a connected therewith to a minimum, since the amount of work which must be done by each relay is relatively small. This in turn reduces the amount of arcing at the ends of the brush wires to a minimum. The winding of each of the magnets 14 on the other hand consists of much fewer turns of coarser wire since the amount of current required and work to be done is relatively great and this large current is readily controlled by the contacts 101 and 102 of each relay with which the corresponding magnet 14 is connected, since the contacts 101 and 102 may be made solely to withstand arcing to the best advantage, as for example said contacts may consist of small carbon blocks which will withstand the arcing action for a considerable time and when they are worn away they may easily be replaced. In connection with the circuit requiring but small current I find it advantageous to use resistances 107 and 108 as for example in the relay actuating circuits and the circuit of the motor 75 respectively, the resistance 107 being connected in the common conductor of the relay actuating circuits.

As shown in Fig. 17, my complete system consists preferably of a controlling mechanism K in which two groups of relay mechanism R and R¹ are mounted, each group being as described above in connection with Figs. 12-15 inclusive. The controlling mechanism is adapted to control the operation of two groups of typewriting machines, a first group being indicated diagrammatically at T¹, T², T³ and T⁴ and a second group being similarly indicated at T⁵, T⁶, T⁷ and T⁸. The typewriters T¹, T², T³ and T⁴ are connected with the controlling mechanism by cables of electrical conductors C¹, C², C³ and C⁴ respectively and the typewriters T⁵, T⁶, T⁷ and T⁸ are similarly connected by cables C⁵, C⁶, C⁷ and C⁸ respectively. The cable C⁴ is connected with a connecting and switching mechanism S⁴ by which the circuits extending to the controlling mechanism K from the typewriter T⁴ may be simultaneously made or broken as desired in a manner to be explained and from the switching mechanism S⁴ connection is made by a cable of electrical conductors C⁹ to the relay contacts of the group of relays R. The cable C⁸ is similarly connected through a similar switching mechanism S⁸ and the latter is connected by a cable C¹⁰ to the relay contacts of the second group of relays R¹. The energizing windings of the relay groups R and R¹ are connected respectively by cables of conductors C¹¹ and C¹² with a reversing switch RS. The reversing switch is also connected by a cable of conductors C¹³ with the contacts of an automatic circuit controlling mechanism A constructed as described in connection with Figs. 12-15 inclusive and also with another cable of conductors C¹⁴ extending to a manually controlled switching mechanism for controlling the energizing circuits of the relays in a manner to be described. The function of the reversing switch is to connect the conductors of the cable C¹⁴ either with the corresponding conductors of the cable C¹¹ or the cable C¹² as desired and at the same time to connect the conductors of the cable C¹³ with the conductors of the cable C¹² or the cable C¹¹. The switch RS also provides for connecting the conductors of either the cable C¹³ or C¹⁴ with the corresponding conductors of both of the cables C¹¹ and C¹² as desired in parallel relation. The reversing switch is provided with an operating handle 109 projecting from the front of the casing of the controlling mechanism by which the connections referred to may be effected. The switching mechanism S⁴ is connected to an operating rod 110 which projects through the front of the cabinet and has secured to its outer end an operating handle 111. The switching mechanism S⁸ is similarly connected by a rod 112 with an operating handle 113. Each of the cables C¹, C², C³, and C⁴ is connected with a switching mechanism, of the same construction as that shown at S⁴, which switching mechanisms are mounted in the cabinet one above another on separate supports and the other terminals of these several mechanisms are connected respectively in parallel and to the corresponding conductors of the cable C⁹. The cables C⁵, C⁶, C⁷ and C⁸ are similarly connected to separate switching mechanisms like the switching mechanism S⁸, the other contacts of which switching mechanisms are respectively connected together in parallel relation and to the corresponding conductors of the cable C¹⁰. The several switching mechanisms referred to are connected with operating rods provided with handles as de- 130

scribed above for the switches S^4 and S^8 , these several handles being shown more clearly in Fig. 18, the handles 111, 114, 115 and 116 controlling connection respectively with the cables C^4 , C^3 , C^2 and C^1 and the handles 113, 117, 118 and 119 controlling connection respectively with the cables C^8 , C^7 , C^6 and C^5 . As a result of the construction described the pulling out of any one of the handles disconnects the corresponding typewriting machine and the pushing in of said handle connects said machine with its relay group for operation thereby. It will be observed that the handles 111, 114, 115 and 116 are disposed in a vertical row and it will be understood that the operating rods extending from the handles are similarly disposed over each other. A common operating mechanism for said rods is provided as follows: The rod 110 has rigidly secured thereto a collar 110^a located between the ears of a yoke 120 suitably mounted on the rods connected with said handles. An operating rod 121 projects forwardly from said yoke 120 and has secured to its outer end an operating handle 122. All of the operating rods are provided with collars in the manner described for the rod 110 as a result of which, movement of the handle 122 moves all four of the rods either inwardly or outwardly as desired and therefore operates all of the corresponding switching mechanisms to their closed or open position. Sufficient clearance is provided between the ears of the yoke 120 to permit individual operation of said rods in any desired combination and the relation of the parts is such that whatever may be the position of the several switching mechanisms connected with said rods, pulling the handle 122 outwardly will move all of the closed switching mechanisms to their open position and moving said handle inwardly will move the open switching mechanisms to their closed position. The construction of the yoke 120 and the relation of the several operating rods to each other is more clearly shown in Fig. 23. The rods connected with the operating handles 113, 117, 118 and 119 are provided with a similar common operating mechanism controlled by a handle 123 operating in the same manner as the handle 122 to produce the same results for the typewriting machines T^5 , T^6 , T^7 and T^8 as produced by the handle 122 for the typewriting machines T^1 , T^2 , T^3 and T^4 . Push buttons 124 and 125 are mounted on the front of the cabinet to respectively start and stop the operation of the automatic controlling mechanism A as desired in a manner to be described.

To complete the controlling mechanism shown in Fig. 17 the cabinet is provided with a cover upon which a manual circuit controlling mechanism B is mounted preferably upon a base-plate 126 so that it may be

moved forwardly from the front of the cabinet somewhat, in the slides 127 carried by the top of the cabinet, to make operation of the mechanism B by the operator more convenient. The manual switching mechanism B consists essentially of keys and key levers arranged preferably in the same manner as the arrangement of the keys on a standard key-board and it may if preferred, consist of a standard typewriting machine having key levers provided with switching mechanism as follows: Each of the key levers 128 as shown in Fig. 19 has connected thereto a downwardly extending rod 129 threaded at its lower end to engage a turnbuckle 130 which also engages the threaded upper end of a lower rod 131, the threads on the ends of the rods being of reverse inclination to effect proper adjustment by means of the turnbuckle. The rod 131 extends through a guide plate 132 of insulating material supported by the frame of the machine B and its lower end rests above spring contacts 133 and 134 carried by a bar of insulating material 135 supported by the frame work of the machine. The contacts 133 and 134 are separated somewhat from each other so there is no electrical contact between them and when the rod 131 is moved downwardly by depression of the key bar 128, it moves between the contacts 133 and 134 making electrical connection between said contacts. The turnbuckles are preferably bars of insulating material to prevent the possibility of short circuits occurring between the several contacts of the machine. Each of the contacts 134 is an individual contact connected to one of the conductors 136 of the cable C^{14} , the contacts 133 being common contacts constructed preferably as indicated in Fig. 20 so that a single strip of contacts extends throughout the length of the bar 135 for operation by a series of key levers 128. For convenience other series of said key levers are connected with corresponding series of spring contacts of the same construction as those just described, carried by insulating bars 135^a, 135^b and 135^c similarly supported from the frame work of the machine B. The contact strip 133 is connected by a wire 137 with a common conductor 138 of the cable C^{14} to which the other similar strips of contacts are also connected as indicated. Each of the key levers is returned to its upper position when released, by a spring 139 and thus electrical connection between the corresponding contacts 133 and 134 is interrupted. It will be observed that the contact construction referred to permits a considerable range of operation of the key levers to accommodate the differences which may exist in the operating strokes of different operators and furthermore for any operation the rods 131 make sliding contact between the spring contacts 133 and 134

thus maintaining good electrical contact between the parts. In this manner the connections between the common conductor of the cable C^4 and the individual conductors of said cable may be effected by manual operation and may be made to serve the same purpose by proper connection of the cable C^4 at its other end as results from the closing of the relay circuits by the brush wires shown and described in connection with Figs. 12-15 above.

Each of the switching mechanisms for controlling connection with the cables C^1-C^8 inclusive is of the same construction and it will be necessary to describe but one of them, as for example the switch S^4 . As shown in Figs. 21 and 22 the switch S^4 consists of a first series of spring contacts 139 secured to an insulating bar 140 mounted upon a shelf or plate 141 which in turn is secured in the cabinet of the controlling mechanism in the position indicated in Fig. 17. These contacts 139 are individual and insulated from each other and are arranged to be engaged by a corresponding series of switch blades 141^a secured to an insulating bar 142 provided with end pivots 143 located below and to the right of contacts 139 for the relation of the parts shown in Fig. 22, said end pivots or bearings 143 being supported in brackets 144 carried by the shelf 141. The bar 142 has secured thereto at one of its ends, an upwardly extending arm 145 to the upper end of which the end of an operating rod 110 is loosely connected so that movement of the operating rod to the right for the relation of the parts shown in Figs. 21 and 22 will rotate the bar 142 and the switch blades connected therewith around to the right in the direction indicated by the arrow in Fig. 22 on the end pivots 143 of the bar. A contact 139 and cooperating switch blade 141^a are provided for each conductor in the corresponding cables connected with the switching mechanism as a result of which movement of the rod 110 serves to interrupt connection between all of the conductors of the cable C^4 and all of the corresponding conductors of cable C^9 . Connection of the contacts 139 to the cable C^4 is indicated in Fig. 22 by the wire 146 and corresponding connection between the switch blades 141^a and the cable C^9 is indicated in the same figure by wire 147, it being understood that the cable C^9 may have any suitable support not shown from the shelf 141 and that its conductors are connected in parallel relation with the several series of switch blades 141^a of the different switching mechanisms employed below the switching mechanism S^4 for the relation of the parts shown in Fig. 17. The conductors of the cable C^{10} are similarly connected with the switch blades of the switching mechanism S^8 and the other switching mechanisms located below said switching mechanism for

the relation of parts shown in Fig. 17. It will be observed that the contacts 139 constitute a convenient terminal strip for the conductors of the cable C^4 so that in wiring the typewriting machines the cables may have any desired length depending upon where the machines are to be located relatively to the controlling mechanism.

The reversing switch RS is constructed preferably as shown in Figs. 24 and 25 and consists of a roller or commutator 148 mounted on suitable end bearings supported in brackets as indicated diagrammatically in Fig. 17 for rotation by the operating handle 109 through an angle of substantially 180 degrees. The roller 148 is of insulating material and is provided with a plurality of slots extending transversely through it in which segments 149 and 150 of conducting material such as copper or brass are inserted, there being as many pairs of segments 149 and 150 as there are circuits to be reversed by the reversing switch, or in other words as many as there are conductors in the cables C^1 , C^2 , C^3 or C^4 . Each pair of segments 149 and 150 is disposed in the same manner in the roller 148 for engagement with four contact springs as indicated in Fig. 24. The first one of these springs 151 is mounted upon a bar 152 of insulating material and for the position of the roller 148 shown in Fig. 24 rests upon the left hand end of the segment 149, this spring being connected by a wire with one of the conductors of the cable C^3 . A second contact spring 153 rests upon the right hand end of the segment 149 in which position it is supported by the front plate 154 of insulating material, said spring being connected by a wire with one of the conductors of the cable C^1 . A third contact spring 155 rests upon the right hand end of the segment 150 and a fourth contact spring 156 rests upon the left hand end of said segment, said contacts being held in place by bars 157 and 158 respectively of suitable insulating material and connected by wires, each with a conductor of the cables C^4 and C^2 respectively, there being a complete set of contact springs 151, 153, 155 and 156 for each pair of segments 149 and 150 which springs are insulated from each other by the insulating mounting plate and bars, and which springs are connected with the wires of the cables C^3 , C^1 , C^4 and C^2 respectively. It will appear that for the position of the roller 148 shown in Fig. 24 the relay group R has its relay windings connected respectively with the circuit closing brush fingers of the automatic circuit controlling mechanism A through the cables C^1 and C^3 , these circuits being closed through the segments 149, and that the relay windings of the relay group R¹ are respectively connected with the corresponding contacts of the manual switching mechanism

B through the cables C¹² and C¹⁴, these circuits being closed through the segments 150. When the roller 148 is moved through substantially 90 degrees around to the right 5 as shown in Fig. 24, each segment 150 establishes electrical connection between a spring 151 and a spring 156 and each segment 149 establishes electrical connection between a spring 153 and a spring 155 and for 10 this position of the roller 148 the relay windings of the relay group R are connected respectively with the contacts of the manual switching mechanism B through the cables C¹¹, and C¹⁴, and the relay windings of the 15 relay group R¹ are connected with the brush fingers of the automatic controlling mechanism A through the cables C¹² and C¹³. In this manner the operation of either group of relays may be controlled either by the operation 20 of the manual switching mechanism or of the automatic switching mechanism by proper operation of the reversing switch and at the same time the other group of relays may be operated by the other of said 25 switching mechanisms. Again, by rotating the roller 148 substantially 45 degrees around to the left from the position indicated in Fig. 24, each segment 149 has resting upon it springs 153, 151 and 156, or in other 30 words the conductors of cables C¹¹, C¹³ and C¹² are connected respectively and both of the relay groups R and R¹ are connected for simultaneous operation by the automatic controlling mechanism and the manual switching mechanism is disconnected from 35 both relay groups; or, by turning the roller 148 around to the right substantially 135 degrees from the position indicated in Fig. 24, each segment 149 has resting upon it 40 springs 153, 155 and 156 connecting the respective conductors of cables C¹¹, C¹⁴ and C¹² together at which time both of the relay groups are connected for simultaneous operation 45 by the manual controlling mechanism and the automatic controlling mechanism is disconnected from both relay groups.

In Fig. 26 I have shown diagrammatically the circuit connections employed throughout my system. In this connection since the electromagnets used for operating the key bars of the several typewriting machines are of the same construction and similarly operated, I show but one of these electromagnets for each of said typewriting machines, for example the electromagnet employed in connection with each said machine for writing the letter "a." Since the special controlling mechanism associated with each typewriting machine is of the same kind and similarly operated from the relay mechanism, and since the control exercised by the relay mechanism in effecting the operation of the special electromagnets is exercised through similar circuits to those employed for operating the key lever magnets, I show the

special electromagnet mechanism for but one of the typewriting machines, for example the machine T⁸. To further simplify the diagrammatic circuit connections shown in Fig. 26, I show but one relay circuit for 70 each group of relays and but one contact closing device of the automatic switching mechanism and the manual switching mechanism for controlling said relay circuits and but one set of reversing contacts 75 for controlling said circuits, it being understood that the circuits are duplicated so that each relay of each group is provided with similar operating circuit and controls similar circuits through the typewriting 80 machine electromagnets.

As shown in this figure, current is supplied to the system by means of main feed wires 159 and 160 extending through main switch MS from any suitable source not 85 shown which may if desired, be the regular lighting circuit available for lighting purposes. The feed wire 159 extends to the automatic switching mechanism A and is also connected with a wire 161 connected in 90 parallel with the switching mechanisms S¹, S², S³ and S⁴ from which switches, supply wires 161^a, 161^b, 161^c and 161^d extend through cables C¹, C², C³ and C⁴ to the typewriting 95 machines T¹, T², T³ and T⁴ respectively where said wires are connected with all of the electromagnets of said typewriters 100 respectively. The feed wire 159 is also similarly connected by wire 162 through switching mechanisms S⁵, S⁶, S⁷, S⁸ to wires 162^a, 105 162^b, 162^c and 162^d through cables C⁵, C⁶, C⁷, C⁸ extending respectively to the typewriting machines T⁵, T⁶, T⁷ and T⁸ in which machines they form common conductors for the various electromagnets. The back contacts 102 of the relays of group R are connected together and by wire 163 with feed wire 160. The back contacts 102^a of the relays of group R¹ are similarly connected together and by wire 164 with feed wire 110 160. The front contacts 101 of the relays of group R are each connected by a wire 165 in parallel relation with corresponding ones of the switch contacts of the switches S¹, S², S³ and S⁴ from which individual 115 connections are made by wires 166, 166^a, 166^b, 166^c through cables C¹, C², C³, C⁴ with the magnets 14 of the machines T¹, T², T³ and T⁴ respectively as a result of which current flows through the wires 166, 166^a, 166^b, 166^c and 166^d simultaneously upon the closing of the corresponding contact 101 against its contact 102 and simultaneously actuates the corresponding electromagnets 14 of the said machines. Each of the front contacts 101^a 120 of the relays of the group R¹ is similarly connected by a wire 167 in parallel relation with corresponding switch contacts of the switches S⁵, S⁶, S⁷ and S⁸ connected respectively by wires 168, 168^a, 168^b and 168^c 125 130

with corresponding magnets 14 of the machines T^s , T^e , T^r and T^b so that closing any one of the contacts 101^a against its back contact 102^a energizes a corresponding one 5 of the electromagnets 14 of each of said machines.

The feed wire 160 is connected by wire 169 through cable C^{14} with the contacts 133 of the manual switching mechanism and 10 each of the contacts 134 of said mechanism is connected by a corresponding wire 170 of the cable C^{14} with one of the switch springs 155 of the reversing switch, as a result of which the wire 169 constitutes a 15 common supply wire for the contacts 133. The feed wire 160 is also connected by wire 171 through resistance 107 with the conducting roller 67 of the automatic switching mechanism, each of the contact fingers 86 20 of which is connected by wire 171 with a corresponding one of the contact springs 151 of the reversing switch, the wire 170 and the wires 171 constituting conductors of the cable C^{13} . The feed wire 159 is connected by wire 172 with one terminal of the winding of each of the electromagnets 81 and 82, the other terminals of said windings being connected respectively with contacts of the push buttons 125 and 124, the other 25 contacts of which push buttons are connected together and by wire 173 with the wire 160. The wire 159 is also connected by wire 174 with contact 78 and contact 77 is connected through resistance 108 by wire 175 30 with one terminal of the motor 75 the other terminal of which is connected by wire 176 with the wire 160. The motor 75 is provided with a shunt field winding 75^a having its terminals connected directly with the wires 159 and 160 in the automatic switching mechanism, so that the motor will stop quickly whenever its armature circuit is 35 opened at the contacts 77 and 78.

The wire 162^a of the cable C^s constitutes a common feed wire for the typewriting machine T^s and besides being connected with one terminal of the winding of each of its electromagnets 14, it is also connected with one terminal of the winding of the 40 electromagnet 18 and by wires 177, 178, 178^a and 179 with one terminal of the windings of electromagnets 14^r, 47^a, 47 and 54 respectively, and by-wires 180 and 181 with one terminal of the motor 29 and the brush 45 38 respectively. The other terminals of the windings of magnets 18, 14^r, 47^a and 54 are connected respectively with wires 182, 183, 184 and 185 constituting individual wires of the cable C^s and extending 50 through the switching mechanism S^s and controlled in the same manner as is each of the individual connections 168^a from the electromagnets 14 of said typewriting machine T^s . The brush 37 is connected by wire 186 with the contact 48

and the contact 49 is connected with a wire 187 extending through the cable C^s and connected through the switch S^s and cable C^{10} with the feed wire 160. The contacts 26 and 27 are connected respectively by 70 wires 188 and 189 with the other terminal of electromagnet 47 and wire 187. The other terminal of the motor 29 is connected by wire 190 with wire 187. As a result 75 of the circuit connections described with the reversing switch in the position indicated in Fig. 26, when any of the switches S^1 to S^8 inclusive is closed the motor 29 of the corresponding typewriting mechanism is started since the wires 162^d and 187 are 80 connected respectively with the feed wires 159 and 160. If now any one of the key levers of the manual switching mechanism B is depressed the pin 131 establishes electrical connection between the contacts 133 85 and 134 closing the following circuit: feed wire 159, wire 162, relay winding 98^a, wire 191 of cable C^{12} , spring 156, segment 150, spring 155, wire 170, contact 134, pin 131, contact 133, wire 169, to feed wire 160 thus 90 energizing the relay and closing the corresponding contacts 101^a and 102^a. This closes the following circuit: feed wire 159, wire 162, contacts of switch S^s , wire 162^d, 95 winding of electromagnet 14, wire 168^a, contacts of switch S^s , wire 167, contact 101^a, contact 102^a, wire 164, to feed wire 160, thus energizing the electromagnet 14. A similar circuit is provided in the manual switching mechanism B and through the 100 reversing switch RS for the relay for actuating each of the electromagnets 18, 14^r, 47 and 54 through contacts of said relay mechanism connected in a similar manner through the switch S^s . Thus at the end of 105 a written line by depressing a proper key at the switching mechanism B, the electromagnet 54 is energized over the following circuit: feed wire 159, wire 162, contacts of switch S^s , wire 162^d, wire 179, winding 110 of electromagnet 54, wire 185, through switch S^s , contacts 101^a and 102^a of the corresponding relay 98^a to feed wire 160. This moves the contact block 50 into engagement with contacts 48 and 49 closing 115 the following circuit from the feed wire 159 over the path above traced to wire 162^d, wire 181, brush 38, slip ring 36, winding 34 of clutch 33, slip ring 35, brush 37, wire 186, contact 48, contact block 50, contact 49, wire 187 through switch S^s and cable C^{10} to feed wire 160. The energization 120 of the clutch operates as above described to move the carriage of the machine T^s to its position for beginning the next written line for which position the contact block 25 is moved into engagement with the contacts 26 and 27 as above described to close the following circuit, the energizing circuit of the electromagnet 54 being at 125 130

this time interrupted by release of the carriage return key of the switching mechanism B; feed wire 159, over the path above traced to wire 162^a, wire 178^a, winding of electromagnet 47, wire 188, contact 26, contact block 25, contact 27, wire 189, to wire 187 and through the connections above described to feed wire 160, thus energizing electromagnet 47 and moving the contact block 50 from engagement with the contacts 48 and 49, thus opening the circuit above traced through the electromagnetic clutch and placing the carriage of the typewriting machine in condition for writing the next line. The wire 184 constituting an individual conductor, extends from electromagnet 47^a through the cable C^a which, for the position of the reversing switch shown in Fig. 26, may be connected in a similar manner to that described above with the feed wire 160 by operation of a carriage release key of the manual switching mechanism so that when it is desired to rotate the platen of the typewriting machine T^a without effecting a complete return of the carriage, this may be done by first operating the carriage return key and immediately releasing it and operating the carriage release key as many time as desired, the effect being that the platen of the typewriting machine will be rotated and the return of the carriage be partly effected as a result of the time element required for complete return of the carriage. Two electromagnets 47 and 47^a are provided to open the circuit through the wire 186 to prevent the possibility of the opening of the circuit through contacts 26 and 27 prematurely stopping the return movement of the carriage of one of the other typewriting machines connected in parallel with the machine T^a, in the event the carriages of said machines do not return in exactly the same time. The switching mechanism B is also provided with a tabulating key and a tabulating release key for controlling independent switch contacts controlling in the manner above described the energization of the electromagnets 14^a and 18 through individual wires 183 and 182 of the cable C^a, the electromagnet 14^a being first energized and then after a sufficient interval to permit the corresponding movement of the carriage, the electromagnet 18 being energized to release the locked condition of the tabulating mechanism described in connection with Figs. 6, 7 and 8 above.

The automatic switching mechanism A is provided with a contact brush 86 corresponding with each of the pairs of contacts 133 and 134 described above in connection with the manual switch mechanism B, which contact brushes, for the position of the reversing switch shown in Fig. 26 control the

operation of the relays of the group R in the same manner above described for the control of the relays of the group R¹ by the manual switching mechanism B. In view of this it will be necessary to trace but one of these circuits as follows: feed wire 159, winding of relay 98, wire 192 of cable C¹¹, contact spring 153, segment 149, contact spring 151, wire 171, brush 86, roller 67, resistance 107, wire 170 to feed wire 160. The closing of the contacts 101 and 102 energizes the electromagnets 14 corresponding with said relay 98 and forming part of the typewriting machines T¹, T², T³, and T⁴ through circuits identical with those described for the typewriting machines T⁵, T⁶, T⁷ and T⁸. To start the operation of the automatic switching mechanism A, the push button 124 is operated closing the following circuit: feed wire 159, wire 172, winding of magnet 82, contacts of push button 124, wire 173, to feed wire 160. The energization of the magnet 82 moves the contact block 76 into engagement with the contacts 77 and 78 closing the motor circuit as follows: feed wire 159, wire 174, contact 78, contact block 76, contact 77, resistance 108, wire 175 to and through the motor 75, wire 176 to feed wire 160. The motor 75 is thus operated and drives the roller 67 in the manner above described and moves the record strip not shown in Fig. 26, under the brushes 86 to permit them to make contact with roller 67 through apertures therein at the proper time to secure the desired sequence of operation of the several magnets of the machines T¹, T², T³ and T⁴. When it is desired for any reason to stop the operation of the switching mechanism A, the push button 125 may be operated closing the following circuit; feed wire 159, wire 172, winding of magnet 81, contacts of push button 125, wire 173 to wire 160. The energization of the magnet 81 moves the contact block 76 from engagement with the contacts 77 and 78 thus opening the circuit through the motor 75. To provide for automatic stopping of the motor at the end of the record on the record strip by a suitable perforation in said strip, a contact brush 86^b is provided in line with said aperture, connected by wire 193 with the winding of the magnet 81 as a result of which when said contact finger 86^b engages the roller 67 through one of said apertures the following circuit is closed: feed wire 159, wire 172, winding of magnet 81, wire 193, contact brush 86^b, roller 67, resistance 107, wire 170, to feed wire 160. This energizes the electromagnet 81 with the same result above described.

With the reversing switch RS rotated through 90 degrees in the direction indicated by the arrow, the segment 149 no longer connects springs 151 and 153 nor does the segment 150 longer connect the springs 155 and 130

- 156 but instead the segment 149 now connects springs 151 and 156 and the segment 150 now connects springs 153 and 155. For this position of the reversing switch, operation of the key lever shown for the manual switching mechanism closes the following circuit: feed wire 159, winding of relay 98, wire 192, spring 153, segment 150, spring 155, wire 170, contact 134, pin 131, contact 133, wire 169, back to feed wire 160. The energization of the relay 98 operates as above described to close corresponding circuits through the magnets 14 of the machines T^1 , T^2 , T^3 , T^4 . For this condition of the reversing switch, engagement between the brush 86 and the roller 67 closes the following circuit: feed wire 159, wire 162, winding of relay 98^a, wire 191, spring 156, segment 149, spring 151, wire 171, brush 86, roller 67, resistance 107, wire 170, back to feed wire 160. The resulting energization of the relay 98^a closes the contacts 101^a and 102^a and operates the corresponding electromagnets 14 of the machines T^5 , T^6 , T^7 and T^8 in the manner above described for the other position of the reversing switch. In other words the operation of the reversing switch as just described changes the control of the relay groups R and R¹ from the automatic switching mechanism A and the manual switching mechanism B respectively to the manual switching mechanism B and the automatic switching mechanism A respectively for the purpose above set forth.
- When the reversing switch is moved from the position shown in Fig. 26 around to the left substantially 45 degrees, the springs 153, 151 and 156 are connected by segment 149, and when the brush 86 engages roller 67 the relays 98 and 98^a are energized in parallel relation over the paths above traced. Similarly, when the reversing switch is moved from the position indicated in Fig. 26 around to the right substantially 135 degrees, the springs 153, 155 and 156 are connected through segment 149 closing contacts 133 and 134 and energizing relays 98 and 98^a in parallel relation over the paths above traced.
- While I have shown my invention in the particular embodiment above described, it will be understood that I do not limit myself to this exact construction as I may employ equivalents known to the art at the time of the filing of this application without departing from the scope of the appended claims.
- What I claim is:
1. In a system of the class described, the combination of a cabinet, a manual switching mechanism on said cabinet, automatic switching mechanism adapted to record strip operation, groups of conductors controlled by said switching mechanisms and extending from said cabinet, switches in said cabinet for interrupting and establishing the continuity of said groups of conductors as desired, and handles for said switches extending to the outside of said cabinet for convenient operation by the operator of said manual switching mechanism.
  2. In a system of the class described, the combination of a cabinet, a manual switching mechanism on said cabinet, automatic switching mechanism adapted to record strip operation, groups of conductors controlled by said switching mechanisms and extending from said cabinet, switches in said cabinet for interrupting and establishing the continuity of said groups of conductors as desired, handles for said switches extending to the outside of said cabinet for convenient operation by the operator of said manual switching mechanism, said conductors being in two main groups for separate control by said switching mechanisms, a reversing switch in said cabinet for interchanging the relation between said two main groups and said mechanisms, and a handle for said reversing switch extending to the outside of said cabinet for operation by said operator.
  3. In a system of the class described, the combination of a cabinet, a manual switching mechanism on said cabinet, automatic switching mechanism adapted to record strip operation, groups of conductors controlled by said switching mechanisms and extending from said cabinet, switches in said cabinet for interrupting and establishing the continuity of said groups of conductors as desired, handles for said switches extending to the outside of said cabinet for convenient operation by the operator of said manual switching mechanism, a base for said manual switching mechanism, and slides on said cabinet engaging said base to permit moving said base forwardly over the front of said cabinet for convenient operation of said manual switching mechanism.
  4. In a typewriting machine of the class described, the combination of a frame, a carriage, tabulating stop mechanism, actuating devices for said mechanism, a first electromagnet for operating said actuating devices, a detent for holding said actuating devices in their operated position, and a second electromagnet for moving said detent to release said actuating devices.
  5. In a typewriting machine of the class described, the combination of a frame, a carriage, tabulating stop mechanism, actuating devices for said mechanism including a rocking bar having a projecting arm, a first electromagnet for rocking said bar, a detent engaging said arm for the rocked

position of said bar, and a second electromagnet for moving said detent from engagement with said arm.

6. In a typewriting machine of the class described, the combination of key-bars, electromagnets arranged in rows from front to rear and connected with said key-bars, and an arcuate support for the electromagnets of each row to equalize the action of 10 said electromagnets on the connected key-bars.

7. In a typewriting machine of the class described, the combination of key-bars, electromagnets arranged in rows from front 15 to rear and connected with said key-bars, an arcuate support for the electromagnets of each row to equalize the action of said electromagnets on the connected key-bars, each of said electromagnets comprising a 20 winding and a plunger, a screw extending from said plunger, a yoke clamped to said screw, and a connecting block of insulating material secured to the end of said yoke.

8. In a typewriting machine of the class 25 described, the combination of key-bars, electromagnets arranged in rows from front to rear and connected with said key-bars, an arcuate support for the electromagnets of each row to equalize the action of said 30 electromagnets on the connected key-bars, each of said electromagnets comprising a winding and a plunger, a screw extending from said plunger, a yoke clamped to said screw, a connecting block of insulating material secured to the end of said yoke, a 35 fixed stop for limiting movement of said plunger, and a bent disk of non-magnetic spring material on said stop.

9. In a typewriting machine of the class 40 described, the combination of key-bars, and electromagnets connected with said key-bars, each of said electromagnets comprising a winding, a plunger, a screw extending from said plunger, a yoke clamped to said 45 screw, and a connecting block of insulating material secured to the end of said yoke.

10. In a typewriting machine of the class 50 described, the combination of key-bars, and electromagnets connected with said key-bars, each of said electromagnets comprising a winding, a plunger, a screw extending from said plunger, a yoke clamped to said screw, a connecting block of insulating material 55 secured to the end of said yoke, a fixed stop for limiting movement of said plunger, and a bent disk of non-magnetic spring material on said stop.

11. In a typewriting machine of the class 60 described, the combination of key-bars, and electromagnets connected with said key-bars, each of said electromagnets comprising a winding, a plunger, a fixed core in said winding, and a disk of non-magnetic spring metal on said stop, said disk having radial

slits in it and bent at its edge to form a 65 spring bumper for said plunger.

12. In an automatic switching mechanism of the class described, the combination of a roller of conducting material for engagement by a record strip, brushes engaging 70 said record strip for control thereby, each of said brushes comprising a metal strip and a plurality of slender spring wires secured thereto for engagement at their free ends with said record strip, said roller having 75 narrow insulating strips extending longitudinally of its surface separating spaced conducting strips of said surface, said record strip having apertures therethrough longer than the width of said conducting 80 strips, and means carried by said roller for maintaining registry of said apertures and conducting strips.

13. In an automatic switching mechanism of the class described, the combination of a 85 first roller for engagement by a record strip, a fixed support, a bar hinged to said support, a pressure roller, arms extending from said bar for supporting said pressure roller, and contact springs extending from 90 said bar for engaging said record strip, whereby rotating said bar moves said contact springs and said pressure roller away from said first roller.

14. In an automatic switching mechanism 95 of the class described, the combination of a first roller for engagement by a record strip, a fixed support, a bar hinged to said support, a pressure roller, arms extending from said bar for supporting said pressure 100 roller, contact springs extending from said bar for engaging said record strip, whereby rotating said bar moves said contact springs and said pressure roller away from said first roller, and a spring tending to hold 105 said bar in a position pressing said contact springs and said pressure roller against said first roller.

15. In an automatic switching mechanism 110 of the class described, the combination of a first roller for engagement by a record strip, a fixed support, a bar hinged to said support, a pressure roller, arms extending from said bar for supporting said pressure roller, contact springs extending from said 115 bar for engaging said record strip, whereby rotating said bar moves said contact springs and said pressure roller away from said first roller, a spring tending to hold said bar in a position pressing said contact 120 springs and said pressure roller against said first roller, and a catch for holding said contact springs and said pressure roller away from said first roller.

16. In a manual switching mechanism of 125 the class described, the combination of key-levers, a conducting pin extending from each key-lever, a pair of separated contact springs

in line with each said pin, whereby each pin when the corresponding key-lever is actuated makes sliding contact with and between its contact springs, and a screw block connecting each said pin with its key-lever to secure adjustment of said pin.

17. In a manual switching mechanism of the class described, the combination of key-levers, a conducting pin extending from each key-lever, a pair of separated contact springs in line with each said pin, whereby each pin when the corresponding key-lever is actuated makes sliding contact with and between its contact springs, and a screw block connecting each said pin with its key-lever to secure adjustment of said pin, said screw blocks being of insulating material.

18. In a manual switching mechanism of the class described, the combination of key-levers, a conducting pin extending from each key-lever, a pair of separated contact springs in line with each said pin, whereby each pin when the corresponding key-lever is actuated makes sliding contact with and between its contact springs, said contact springs being disposed in a row, and a conducting strip connected with one contact spring of each said pair of contact springs.

19. In a manual switching mechanism of the class described, the combination of key-levers, a conducting pin extending from each key-lever, a pair of separated contact springs in line with each said pin, whereby each pin when the corresponding key-lever is actuated makes sliding contact with and between its contact springs, and a guide plate of insulating material for said pins.

20. In an automatic switching mechanism of the class described, the combination of a roller of conducting material for engagement by a record strip, brushes engaging said record strip for control thereby, said roller having narrow insulating strips extending longitudinally of its surface separating spaced conducting strips of said surface, said record strip having apertures therethrough longer than the width of said conducting strips, and means carried by said roller for maintaining registry of said apertures and conducting strips.

21. In an automatic switching mechanism of the class described, the combination of a roller of conducting material for engagement by a record strip, brushes engaging said record strip for control thereby, said roller having narrow insulating strips extending longitudinally of its surface separating spaced conducting strips of said surface, said record strip having apertures therethrough longer than the width of said conducting strips, and means carried by said roller for maintaining said apertures in centered relation to said conducting strips.

22. In a system of the class described, the combination of a cabinet, a manual switch-

ing mechanism on said cabinet, automatic switching mechanism adapted to record strip operation, groups of conductors controlled by said switching mechanisms and extending from said cabinet, switches in said cabinet for interrupting and establishing the continuity of said groups of conductors as desired, handles for said switches extending to the outside of said cabinet for convenient operation by the operator of said manual switching mechanism, said conductors being in two main groups for control by said switching mechanisms, and a reversing switch in said cabinet for connecting either group of said conductors with either of said switching mechanisms and if desired for connecting both groups of said conductors simultaneously with either of said switching mechanisms.

23. In a system of the class described, the combination of a cabinet, automatic switching mechanism adapted to record strip operation, groups of conductors controlled by said switching mechanism and extending from said cabinet, said conductors being in two main groups for control by said switching mechanism, and a reversing switch in said cabinet for connecting either group of said conductors with said switching mechanism and if desired for connecting both groups of said conductors simultaneously with said switching mechanism.

24. In a system of the class described, the combination of a cabinet, automatic switching mechanism adapted to record strip operation, groups of conductors controlled by said switching mechanism and extending from said cabinet, switches in said cabinet for interrupting and establishing the continuity of said groups of conductors as desired, handles for said switches extending for convenient operation by an operator, said conductors being in two main groups for control by said switching mechanism, and a reversing switch in said cabinet for connecting either group of said conductors with said switching mechanism and if desired for connecting both groups of said conductors simultaneously with said switching mechanism.

25. In a typewriting machine, the combination with a main frame, of a platen carriage mounted to slide thereon, means to draw the carriage from right to left, tabulating stops adjustable to determine the limit of such movement, a tabulating key bar, means to depress said key bar automatically, an automatic means to hold the tabulating mechanism in operated position upon the depression of said key bar, an electromagnet to release the automatic means, a circuit through said electro-magnet, and means to close said circuit operated by the tabulating key bar depressing means.

26. In a typewriting machine, the combination with a main frame, of a platen carriage mounted to slide thereon, means to draw the carriage from right to left, a tabulating stop adjustable to determine the limit of such movement, a tabulating key bar, an electro-magnet to cause the depression of the tabulating key bar when it is energized, a master roll with perforations to close the circuit through said electro-magnet, an automatic means to hold the tabulating mechanism in operated position upon the depression of said key bar, an electro-magnet to release said automatic means, a circuit through said second electro-magnet, ¹⁵ and means to close said circuit operated by the master roll.

In witness whereof, I hereunto subscribe my name this 30th day of March, A. D. 1921.

R. WILSON MORE.
